UNITED STATES PATENT OFFICE.

PHILIP C. ARNOLD, OF EAST HAMPTON, CONNECTICUT, ASSIGNOR TO THE BEVIN BROTHERS MANUFACTURING COMPANY, OF EAST HAMPTON, CONNECTICUT, A CORPORATION OF CONNECTICUT.

BELL.

No. 856,995.

Specification of Letters Patent.

Patented June 11, 1907.

Application filed April 7, 1904. Serial No. 202,066.

To all whom it may concern:

Be it known that I, PHILIP C. ARNOLD, a citizen of the United States, and a resident of East Hampton, in the county of Middlesex and State of Connecticut, have invented certain new and useful Improvements in Bells, of which the following is a specification.

The invention relates to bells and more particularly to the specific class of bells known as cow bells and more particularly to such a bell of the drawn or struck up type.

The object of the invention is to provide a bell which will give an extremely clear, loud sound free from such vibration as sometimes muffles or retards the sound of a gong.

A further object is to provide a cast bell or a bell struck up or drawn up from a piece of metal and providing a loop or strap eye therefor secured to the bell in such manner as to make it almost an integral part thereof.

A still further object is to produce an extremely simple form of bell with a special means of applying a loop or attaching means thereto.

Referring to the drawings:—Figure 1 is a plan view of a bell embodying the invention with the loop broken in section. Fig. 2 is a side view of a bell with parts broken away to show construction. Fig. 3 is a transverse sectional view through the bell and loop. Fig. 4 is a perspective view of the loop. Fig. 5 is a transverse, sectional view showing the loop before the shoulders are upset against the bell body.

In the accompanying drawings the character *a* denotes the bell body which is preferably formed by drawing up a piece of metal. This bell body is provided at its upper end with perforations *b c d* and these perforations co-operate with parts on a loop *e* to securely hold the bell body and loop together. The loop *e* is also formed from sheet metal blanked out and provided with a central dependent portion *f* comprising the two down turned ends *f' f''* of the loop *e*. These down turned ends are perforated as at *g* to provide a means for securing the hook of the striker or tongue wire *g'*.

On either side of the down turned portions *f' f''* are tangs or lugr *h h'* preferably formed by forcing out the metal from the body of the loop *e*. The down turned por-

tions *f' f''* have shoulders *i* on opposite edges thereof and the member *f* comprising the two down turned portions is arranged to be inserted through the perforations *b* in the bell body. The tangs or projecting lugs *h h'* also project through the perforations *c* and *d*. When the parts are assembled in this position a tool is applied to the shoulders *i* and they are forced downward and outward against the inner surface of the bell body at opposite ends of the perforation *b*. The tangs or lugs *h h'* are also securely forced inward against the inner surface of the bell body thus providing a positive lock between said body and the loop *e*. It is to be noted that the two lugs or tangs *h h'* are bent inward in the line of the loop *e*, while the shoulders *i* are knocked down and forced outward transversely to the loop. This gives a very firm fastening and is one of the essential parts of the invention.

The tang or striker *k* is of somewhat peculiar form and comprises a cast striker member having radially projecting arms *k'* with a stem *k''*, the latter cast about the wire *g'*. The radially projecting arms *k'* extend to a considerable distance beyond the center of the tongue on either side and thus afford a comparatively light tongue which strikes the gong at single points giving a very clear, sharp detonation.

Obviously the form of the loop *e* might be varied to a considerable extent and its tangs and projecting parts punched out and bent in different manners without departing from the spirit or intent of the invention which contemplates providing a plurality of holding portions on the loop arranged to project through the gong body and to be secured thereto by being pressed firmly against the inner surface.

What I claim as my invention and desire to secure by Letters Patent is:—

1. In combination with a bell body having a plurality of perforations, a loop provided with a tongue supporting member provided with lugs and with lugs to be inserted through the perforations, the lugs of the loop and the lugs of the tongue supporting member arranged when bent, to form shoulders extending both laterally and longitudinally of the loop.

2. In combination with a bell body having

a plurality of perforations, a loop having lugs projecting therefrom and arranged to be inserted through independent perforations and bent to secure the loop in place said loop having a lug adapted to be upset against the bell body and forming a support for the striker or tongue.

3. In combination with a bell body having a plurality of perforations, a loop having lugs projecting through the perforations and secured within the bell body, the ends of the loop also projecting through perforations and forming a support for a tongue and having shoulders secured against the inside of the bell body.

4. In combination with a bell body, a loop, the meeting ends of said loop having down-turned parts projecting through the bell body, and provided with shoulders arranged to be upset against the inner surface thereof and also forming a support for the tongue.

5. In combination with a bell body having a plurality of perforations, a loop having up-turned ends and lugs arranged to register with said perforations, said lugs being upset against the inner surface of the bell body, and a striker or tongue dependent from the down-turned ends of the loop.

6. In combination with a bell body, a loop having its adjacent ends turned down, shoulders formed on said down turned ends and arranged to project within the bell body, lugs

projecting from the loop on opposite sides of the adjacent down turned ends arranged to project through the bell body, said shoulders 35 and lugs adapted to be upset against the bell body.

7. In combination with a bell body, a loop having its adjacent ends turned down, shoulders formed on said down turned ends and 40 arranged to project within the bell body, lugs projecting from the loop on opposite sides of the adjacent down turned ends arranged to project through the bell body, said shoulders and lugs adapted to be upset against 45 the bell body, a striker, and means for securing said striker to the down turned end members of the loop.

8. In combination with a bell body having a plurality of independent perforations, a 50 loop formed from a single piece of material and having its adjacent ends down turned from the loop, lugs formed integral with the loop and projecting therefrom substantially parallel with the down turned end portions 55 said down turned end portions and lugs arranged to register with the perforations of the bell body and a tongue loosely secured to the down turned end portions.

PHILIP C. ARNOLD.
